CLAIM

The ornamental design for a protective end cap for a furniture leg, as shown and described.

DESCRIPTION

FIG. 1 is a top perspective view of a protective end cap for a furniture leg, showing my new design;

FIG. 2 is a bottom perspective view;

FIG. 3 is a bottom plan view; and

FIG. 4 is a top plan view.

The furniture leg fragmentarily depicted in FIG. 1 has been shown for illustrative purposes only.

FIG. 1

FIG. 2

FIG. 3

FIG. 4
